UNITED STATES PATENT OFFICE

2,520,460

GAME DISK PROJECTOR

Charles A. Ford, Clifton, N. J.

Application May 20, 1947, Serial No. 749,185

2 Claims. (Cl. 124—7)

1

This invention relates to improvements in game apparatus; and the invention has reference, more particularly, to a novel game apparatus whereby a playing piece is adapted to be tossed or flipped by a manipulatable projecting means toward a pocket target adapted for the reception thereof.

The invention has for an object to provide a novel game apparatus comprising a support having at one end a target means provided with a multiplicity of playing piece receiving pockets of various selected scoring values, and having at the other end an adjustable catapult to which a playing piece, preferably in the form of a rubber disc, may be applied, and, then by manipulated operation of said catapult, thereby tossed or flipped toward the target.

The invention has for a further object to provide a novel game apparatus of the kind described comprising a flat, horizontally disposed board of suitable width and length adapted to provide a playing field, upon the forward portion of which is mounted the manipulatable catapult device, and over the rearward portion of which is mounted the target; said board being surrounded by a framing comprising upstanding bounding sides and ends, the portions of said sides and ends contiguous to the target being of increased height to provide a back stop structure; and said board and its framing being adapted, if desired, to be supported at a suitable playing level by leg portions which are affixed to the corners thereof.

The invention has for another object to provide a game apparatus of the kind described, wherein the target is formed by intersecting longitudinal and transverse division or partitioning members adapted to provide a multiplicity of perpendicularly open pockets; said target being hingedly connected to the contiguous end of the playing board framing, whereby to be capable of upswinging movement relative to the underlying board surface so as to expose playing pieces which have been deposited in the target pockets, to thereby render said pieces accessible for withdrawal from beneath the target, and thus recoverable for subsequent play.

Still another object of the invention is to provide a combination of the board and its framing in such relation as to provide a storage compartment within the framing and beneath the board for the reception of legs and removable height extending portions of the rear side and end of the framing, when these parts are dis-

2

assembled and packed together for shipment or storage with the board.

Other objects of this invention, not at this time more particularly enumerated, will be understood from the following detailed description of the same.

An illustrative embodiment of this invention is shown in the accompanying drawings, in which:

Fig. 1 is a perspective view of the game apparatus made according to and embodying the principles of this invention;

Fig. 2 is a longitudinal sectional view of the same; and Fig. 3 is an enlarged fragmentary perspective view of the playing piece engaging end of the catapult device with which the game apparatus is equipped.

Similar characters of reference are employed in the hereinabove described views, to indicate corresponding parts.

Referring to the drawings, the reference character 10 indicates the board, the top surface of which provides the playing field of the game. Said board is rabbeted into a surrounding framing comprising main side members 11 and main end members 12. The board 10 is positioned relative to the top and bottom edges of said side and end members so as to be disposed intermediate said edges, whereby the upper portions of said side and end members provide an upstanding wall surrounding the top or playing field surface of the board, while the lower portions of said side and end members provide the sides and ends of a compartment 13 beneath the board, said compartment being adapted for purposes to be hereinafter explained.

The playing board is preferably sized to provide a playing field approximately upwards of four feet long by two feet wide, surrounded by a main upstanding wall, formed by the upper portions of said main side and end members 11—12, which is of approximately two inches in height.

Mounted over the rearward end portion of the playing field surface of the board 10 is a target structure which approximates in width of said playing field surface, and of a length substantially corresponding to such target width. Said target structure is formed by a plurality of upstanding intersecting transverse and longitudinal division or partitioning members 14 and 15, suitably joined together. As thus formed, the target provides a multiplicity of target pockets 16 which are open top and bottom, but which are closed

at the bottoms when the target normally stands or rests upon the playing field surface of the board 10. The target pockets are of rectangular, and preferably of square, cross-sectional shape, and of dimensions somewhat exceeding the diameters of the playing discs to be subsequently described, being of depth preferably somewhat less than the height of the main side and end walls 11 and 12. The number of pockets with which the target is provided is subject to variation, but preferably comprises five rows thereof, each row comprising five pockets, thus making twenty-five pockets in all.

The target structure is hinged at its back end to the adjacent end wall member 12 of the framing of the board 10 by hinging elements 17, and is provided, in connection with its front or free end, with a handle member 18. By reason of such hinged relation of the target structure relative to the playing field board and its walls, said target may be upswung from its normal at rest position upon the board, as shown by the broken line representation thereof in Fig. 2. By thus upswinging the target, playing discs which have lodged in the pockets 16 thereof during the playing of the game, may be accessibly exposed, subject to recovery by withdrawal to the front end of the playing field board. Such playing disc recovery operation may be facilitated by use of the rake 19 shown in Fig. 1.

In order to provide a back-stop structure around the sides and back of the target, auxiliary side and end back-stop walls 20 and 21 of extended height are affixed to the contiguous portions of the main side and end walls 11 and 12. Preferably, these auxiliary side and end back-stop walls 20 and 21 are detachably connected with said side and end walls 11 and 12. A convenient means for so detachably joining these wall parts together in operative assembled relation comprises the provision of tongues 22 of reduced thickness, which depend from the bottom edges of the auxiliary side and end back-stop walls 20 and 21, and which are adapted to be entered in conforming sockets 23 with which the upper portions of the main side and end walls 11 and 12 are provided. When said tongues 22 are entered in said sockets 23, transverse coupling pins or dowels 24 are removably engaged therethrough, thus securing the parts together in operative assembled relation.

A catapult device is affixed to the forward end portion of the playing field board midway of the sides of the latter, and so as to be disposed in suitably outwardly spaced relation to the game target. This catapult device comprises a supporting block or column 25 of suitable height, which is arranged in upstanding relation to the board surface. Supported on the top end of said block or column 25 is one end of a catapult member 26, which comprises an elongated strip of springy metal or other suitable resiliently flexible material, and which is of suitable length, width and thickness. The block or column 25 is affixed to the playing field board 10 by a bolt 27 which extends axially therethrough, and through the supported end of said catapult member 26, these parts being clamped together by a main nut, preferably in the form of a wing-nut 28, which is screwed onto the upper free end portion of said bolt 27. The base portion of the wing-nut substantially matches the top surface of block 25 in size and form for a purpose which will appear later. The catapult member 26, as thus supported, is capable of laterally swinging angu-

lar adjustment, to the left or right, about the axis of the bolt 27. The wing-nut 28 is tightened home sufficiently to both firmly anchor the supported end of the catapult member 26 to the top of the block or column 25, and yet allow the desired swinging movement of the catapult member, whereby to permit desired angular adjusting movement thereof by the player preparatory to use thereof in play; frictional resistance being set up which is sufficient to hold the catapult member against displacement from selected angularly adjusted position when manipulated in play. The wing-nut 28 having been adjusted to attain such end, the same is fixed against accidental loosening by a jam or lock nut 29 which is threaded onto the bolt 27 above the wing-nut. The catapult member 26, as thus operatively mounted, extends toward the front end of the playing field board 10, so as to be easily accessible for control and use by a player. At its free end portion, the catapult member 26 is provided with a pair of transversely spaced stop ears or abutments 30 intermediate which is provided a finger piece 31, which extends outwardly behind the space between said stop ears or abutments, and which is preferably somewhat uptilted relative to the normal top face plane of said catapult member. The position of the catapult on the playing board is such that the finger piece will be substantially a finger length inward from the central depressed portion 12' of the front wall member 12, as shown in Fig. 2. The said depressed portion of the wall may thus be used as a hand-rest. By resting the hand while pressing the finger piece downward and then releasing it, greater precision in manipulation of the catapult may be attained than if no hand-rest were available.

The playing pieces for use in playing the game comprise a plurality of flat circular discs 32 made of rubber or of other comparatively soft but shape retaining material. The discs 32 are of uniform size, and of suitable thickness; the diameters thereof being somewhat less in length than the widths and lengths of the target pockets 16, whereby to be capable of entering said pockets. Any selected number of playing discs 32 may be provided; ten such discs has been found to afford a satisfactory number thereof.

The target pockets 16 are suitably identified by various selected individual scoring value indicia desired to be assigned thereto (see Fig. 1). Preferably pockets in the central areas of the target will be assigned comparatively high values, while outlying pockets will be assigned progressively reduced values.

In playing the game, the player applies a playing disc 32 upon the free end of the catapult member 26, so that the same abuts and is stopped against the stop ears or abutments 30, thereupon, by pressing down upon the finger piece 31, the player tensionally flexes the catapult member to the degree judged adequate to effect a desired cast and resultant trajectory of the playing disc toward a selected area of the target, whereupon the catapult member is released so as to spring upward and thus transmit casting force to the playing disc, whereby to toss or flip the same through the air toward the target, and so that the disc will, at the end of flight, fall into a pocket of the latter. The player repeats these operations until a desired predetermined number of discs have been cast. In repeating the operations, the player may swing the catapult member 26 to the left or right, as the case may be, to predetermine a desired angle of flight judged to

direct the played disc to selected areas of the target and the pockets therein located. After the player has played the assigned number of pieces, the scoring values of target pockets in which the played pieces have lodged are totaled to determine the player's score for that inning. In competitive play, the competing players successively take their turns or innings of play; any number of turns or innings may be optionally allowed, and the player having the highest accumulated score will be determined the winner.

Due to the manner in which the catapult member is clamped between the substantially matching opposed faces of base block 25 and wing-nut 28, flexing action of the catapult member will be smooth and practically noiseless because of the lack of play between said member and any normally contacting parts of the structure. This desirable condition exists regardless of the angular disposition of the catapult member in azimuth with relation to its pivotal axis.

The framed board 10 is preferably provided with supporting legs 33 of suitable length to support the same at a convenient height or level for use, but it will nevertheless be understood that such legs may be omitted and the framed board may be otherwise supported, as e. g. upon a table top, counter or like surface. When the legs 33 are provided, the same are preferably attached to the corner portions of the framed board 10.

The game apparatus may be constructed so as to be capable of being knocked down or disassembled for convenient storage or transportation. To this end, the auxiliary side and end back-stop walls 20 and 21 may be removed by striking out the coupling pins or dowels 24, the legs 33 may also be removed, and the catapult member likewise removed if desired. When these parts are thus disassembled, the same together with the playing discs may be packed into the compartment 13 beneath the board 10, whereupon the thus knocked down apparatus may be boxed or crated for shipment or storage; or, if desired, the open side of the compartment 13 may be covered and closed by suitable means (not shown).

From the above description it will be apparent that the instant invention provides a novel game apparatus well adapted to afford an interesting pastime, and one requiring exercise of skill upon the part of the players.

Having now described my invention, I claim:

1. A playing piece catapult means for a game board having a target area at its inner end por-

tion, the catapult means comprising a base block affixed to the outer end of the game board to upstand therefrom, said base block having a top surface, a vertical pivot bolt rising axially from the base block to project above its top surface, a catapult member in the form of a flat strip of resilient material having its inner end portion superposed upon the top surface of the base block, said inner end portion of the catapult strip having an aperture through which the pivot bolt projects whereby to pivotally mount the strip on the base block for lateral angularly adjusted disposition, a clamping nut threaded on the projecting portion of the pivot bolt with its bottom 10 in clamping engagement with the catapult strip, said catapult strip having a flat seating surface at its free end portion for a disc-shaped playing piece, a finger piece of reduced width integral with and extending outwardly from the free end 15 portion of the catapult strip, portions of the catapult strip bordering opposite sides of the finger piece being formed to provide tongues integral with said strip, said tongues being upwardly and inwardly curled to provide laterally spaced abutments, said abutments being adapted to straddle a disc-shaped playing piece deposited on the seating surface of the catapult strip whereby to center said playing piece on the latter.

2. A playing piece catapult means as defined 20 in claim 1, including a hand rest rising from the outer end portion of the board by which the catapult means is supported, said hand rest being disposed a finger length distance outwardly from the finger piece end of the catapult means.

CHARLES A. FORD.
